UNITED STATES PATENT OFFICE

2,405,491

IRONING MACHINE

Kendall Clark, Oakwood, Ohio, assignor to General Motors Corporation, Dayton, Ohio, a corporation of Delaware

Original application May 21, 1938, Serial No. 209,227. Divided and this application January 26, 1943, Serial No. 473,621

13 Claims. (Cl. 312—2)

1

This invention relates to an ironing machine, and more particularly to a power driven ironing machine contained within a folding cabinet.

This application is a division of my copending application Serial No. 209,227, filed May 21, 1938, now Patent 2,379,788, patented July 3, 1945.

An object of this invention is to provide a novel type of folding ironer cabinet, the sides of which become working shelves for the ironer when the cabinet is unfolded.

Another object of this invention is to provide a folding cabinet for an ironer or the like, which folds into a package having relatively small horizontal extent, thus being particularly useful where floor space is at a premium.

Further objects and advantages of the present invention will be apparent from the following description, reference being had to the accompanying drawings wherein a preferred form of the present invention is clearly shown.

In the drawings:

Fig. 1 is a perspective view of one form of the ironer with the cabinet unfolded, as embodied in the present invention;

Fig. 2 is a perspective view showing the cabinet partially folded;

Fig. 3 is a perspective view showing the pedal base folded into the cabinet;

Fig. 4 is a perspective view showing the left leg folded into the cabinet;

Fig. 5 is a perspective view showing the cabinet folded down against the right leg;

Fig. 6 is a perspective view of the folded ironer as it appears when not in use;

Fig. 7 is a detailed view showing the latching mechanism for retaining the pedal base and the left supporting leg of the ironer during the folding of the ironer cabinet, and taken along the line 7 of Fig. 8;

Fig. 8 is a section taken along the line 8 of Fig. 7;

Fig. 9 is a section taken along the line 9 of Fig. 7;

Fig. 10 is a section taken along the line 10 of Fig. 9;

Fig. 11 is a cross-sectional view of the hinges, in open position, used to mount the extension 4 on table top 1;

Fig. 12 is a view similar to Fig. 11, but showing the extension 4 in folded position;

Fig. 13 is a cross-sectional view showing details of the strap 50; and

Fig. 14 is a cross-sectional view showing details of the catches between extension 4 and barrier 5;

2

Fig. 15 is an enlarged vertical cross-sectional view taken along the line 15—15 of Fig. 1;

Fig. 16 is a horizontal cross-sectional view taken along the line 16—16 of Fig. 17;

Fig. 17 is a view taken along the line 17—17 of Fig. 1, also on enlarged scale;

Fig. 18 is a horizontal cross-section taken along the line 18—18 of Fig. 4, one corner only being shown;

10 Fig. 19 is a vertical cross-section taken along the line 19—19 of Fig. 15;

Fig. 20 is an enlarged top view of a corner of the table top 1;

Fig. 21 is a cross-section taken along the line 21—21 of Fig. 20;

Fig. 22 is an enlarged view of an upper corner of leg 7;

Fig. 23 is a top view of Fig. 22; and

Fig. 24 is a horizontal cross-section taken along 20 the line 24—24 of Figs. 8 and 10.

Any type of ironer construction may be used. By way of illustration the ironer disclosed in my copending application S. N. 209,227, now Patent No. 2,379,788, patented July 3, 1945, is shown.

25 The mechanism is mounted on a folding work table which becomes a cabinet enclosing the ironer when folded.

The ironer as shown in Fig. 1 is fastened to the top of the work table 1. Additional working surface is provided by a front shelf extension 2 hinged to the work table 1 by hinges 2a. In a similar manner the working surface is extended to the rear by the rear shelf 3 also hinged to the table 1. A side extension 4 is also provided and is hinged to the table 1 by hinges 4a. These hinges may be of the double fulcrum variety shown in Figs. 11 and 12. For example, the leaf 70 may be secured to the extension 4 and may be fulcrumed at 71 to the movable leaf 72. The leaf 72 may be fulcrumed at 73 to the leaf 74

40 which is secured to the table top 1. The movable fulcrum 71 swings from the position shown in Fig. 11 to that shown in Fig. 12, the operator exerting a slight lifting movement to the extension 4. To prevent articles from falling off the rear of the work table a vertical barrier 5 extends upward from the rear edge of the shelf 3 and preferably is fixedly secured to the shelf 3 at right angles thereto. The table 1 is supported on legs 6 and 7 which carries a pedal base 8, having control 45 pedals 9 and 11. The legs 6 and 7 are hinged to the table 1, and the pedal base is hinged to the lower end of leg 7. The pedal base 8 is provided with hooks 8a which fit into slots 6a in legs 6.

50 This cabinet may be folded into a compact case

which rests on the base 10 fixed to the lower end of leg 7.

Fig. 2 shows the cabinet partially folded. The three shelf extensions 2, 3 and 4 are folded up and become two sides and an end of the protecting cabinet. The vertical barrier 5, attached to the rear shelf extension, becomes the upper or third side of the cabinet. The original work table top 1 forms the under or fourth side of the cabinet. Suitable frictional catches may be provided to hold these sides in folded position. For example, the barrier 5 may be provided with a metal or leather strap 50 (Fig. 13) which is provided with a recess 51, which receives the button 52 carried by the extension 2. The button 52 snaps into and out of the recess 51 in the well known manner. Likewise, the extension 4 may be provided with buttons 53 (Fig. 14) which snap into and out of recesses 54 in the edge of barrier 5. The extension 4 is moved to or from engagement with barrier 5 while barrier 5 is secured to extension 2.

Fig. 3 shows the cabinet more fully folded. The pedal base 8 is folded on its hinges against the right vertical leg 7, as indicated by the dotted lines and the small permanent base 10 of the machine is now revealed. A small latch (to be described in detail later) holds the pedal base 8 in the folded position.

Fig. 4 shows the cabinet more fully folded, the left leg 6 of the ironer being folded up under the table top 1. A small latch (to be described in more detail later) holds the left leg in the folded position.

The ironer cabinet is now folded down against the right leg 7 as shown in Fig. 5.

The resulting unit, as shown in Fig. 6, is a neat cabinet enclosure for the ironer that occupies very little floor space and is so small that it can be readily stored in any portion of a kitchen or laundry. A pair of small wheels 12 on the cabinet base 10 are provided to aid in moving the unit.

To unfold the ironer, as shown in Fig. 6, the operator grasps a small handle 15 and raises the left end of the cabinet to a position slightly higher than that shown in Fig. 4. Automatic latches (to be described in more detail later) first release the left leg 6 and subsequently the pedal base 8. The pedal base 8 engages the left leg 6, the hooks 8a entering and resting in the slots 6a. The cabinet is then lowered until the left leg 6 bears on the floor, and the ironer appears as shown in Fig. 2. The sides are then unfolded, and the ironer appears as shown in Fig. 1 and is ready to use. The pedal base 8 is provided with pedals 9 and 11 which are connected with cable controls 102 and 108 for the ironer.

Details of the automatic latching mechanism are shown in Figs. 7 to 10. The table top 1 preferably is a sheet metal panel having side flanges 55. The leg 6 preferably is a sheet metal panel having side flanges 56 and an end flange 57 reinforced by an angle iron 58. The leg 7 is a sheet metal panel having side flanges 59. The pedal base 8 is a sheet metal panel having side flanges 60. The end of leg 6 is provided with a pair of feet, as illustrated in Fig. 1.

The table top 1 is hinged to the leg 7 by pins 133 which pass through flanges 55 and 59 of top 1 and leg 7. The pins 133 also form fulcrum supports for levers 142 inside the flanges 55. The flanges 55 also carry pins 138 which form fulcrum supports for latches 137. The flanges 55 also

carry pins 139 which support the ends of latches 137.

The latches 137 have hooks 140, with tapered lower edges. The flanges 56 of leg 6 have outwardly directed projections 136 which hook over the hooks 140 and retain the leg in raised position until the unfolding operation is started.

The flanges 55 of the top 1 carry right angled brackets 150 to which are riveted spring latches 134 having hooks 134a. When the pedal base 8 swings upwardly its end, 151, hooks under hooks 134a, so that the leg 8 is retained in its folded, upper position until the unfolding operation is started.

Further details are as follows: The leg 6 is hinged to the top 1 by means of a pin 109, which is welded to the flange 55 of the top 1 and which loosely passes through flange 56.

The leg 7 has, at its upper corners, a bent leaf 170, which cooperates with the latch 134 to lift the latch 134 when the top 1 is moved to the position 146, as indicated in Fig. 10. The leg 7 also has openings 175 at its upper corners to receive the flanges 55 of the table top 1.

The pedal base 8 is provided with two flanged openings 171 and 172 in which the pedals 9 and 11 are hinged by hinges 173. The base 8 also has an end flange 174 and two end ears 111 through which the hinge pins 110 loosely extend from the leg 7 and base 10. The pins 110 may comprise a bolt having a head 176 over which an extended threaded nut 177 is placed to clamp the leg 7 and base 10 together. The end of the bolt constitutes the pin 110 through which the end ears 111 are hinged.

Rods 101 and 105 have bearings in the flanges of openings 171 and 172 and in flange 174. The rod 101 is bent at 103, with the end 103a attached to the rod or cable 108. The other end of rod 101 is bent at 107, and again at 108, where it is provided with a pulley 179 to cooperate with the bottom of pedal 9. Whenever the pedal 9 is depressed, it depresses pulley 179 and swings rod 101 clockwise, thus lowering the end 103a which is connected to the cable or rod 108.

The rod 105 is bent at 104, the end 104a being connected with the cable or rod 102. The other end of the rod 105 is bent at 108 and again at 101, where it is provided with a pulley 182 to cooperate with the pedal 11. Whenever the pedal 11 is depressed, the pulley 182 is depressed and the rod 105 is turned clockwise, thus lowering end 104a together with cable or rod 102.

When the pedal base 8 is swung upward, on the pins 110, the pedals 9 and 11, together with the bent portions 103 and 104, fold inwardly, thus allowing the face of pedal base 8 to come into proximity of the face of leg 7.

The base 10 includes a bottom pan 190 having flanges 191 and 192, and a vertical pan 193 having flanges 194 and 195.

During the unfolding operation the left leg 6 is automatically released by lifting the left end of the cabinet to a position indicated by the line 144 in Fig. 7. Levers 142 pivoted on pins 133 engage an extension 143 of the right leg 7. Levers 142 also engage latches 137. The lifting of the left end of the cabinet inclines the table top 1 to the position shown by the dotted line 144 and causes a counter-clockwise reaction in the levers 142, which, in turn, impart a clockwise reaction in latches 137 to unhook the latches 137 from the projections 136 and release the left leg 6 so that it can swing down, as indicated by the dotted lines in Fig. 4. Additional lifting of the left end

of the cabinet inclines the table top 1 to the position shown by the dotted line 146, in Fig. 10, which automatically unhooks the spring latches 134, by lifting them above the edge of pedal base 8 and releases the pedal base 8 so that it can swing down, as indicated by the dotted lines in Fig. 3.

In operation, the machine assembly, as shown in Fig. 6, is moved to the location where it is intended to be used. The operator then separates the upper cabinet mechanism from the right hand leg 7 and base 10 by lifting on handle 15. When the upper section is raised to the position shown by the dotted lines in Fig. 5, and line 144 in Fig. 7, the left hand leg 6 is automatically released by the reactions produced in latches 142 and 137, so that it can swing down as indicated by the dotted lines in Fig. 4. Similarly, a little further lifting on the handle 15 to swing the cabinet to a position indicated by the line 146 in Fig. 10 automatically releases the base section 8 by lifting the latches 134 from the edge of the base 8 and allowing the base 8 to swing down, as indicated by the dotted lines in Fig. 3. The shelves 2 and 4 and the back and cover 3 and 5 are then unfolded to the position shown in Fig. 1, for operation of the ironer.

When the ironing operation is finished, the operator then folds the cabinet by folding upwardly the sides and ends 2, 3, 4 and 5 to the position shown in Fig. 2. Thereafter he folds the base 8 upwardly as indicated by the dotted lines in Fig. 3, after which he folds the leg 6 upwardly as indicated by the dotted lines in Fig. 4. Thereafter he lowers the main body of the cabinet downwardly, as indicated by the dotted lines in Fig. 5, so that the cabinet is now in vertical position, as indicated in Fig. 6. The cabinet may then be rolled on rollers 12, by a slight tilting movement, to its place of storage.

While the form of embodiment of the invention as herein disclosed constitutes a preferred form, it is to be understood that other forms might be adopted, all coming within the scope of the claims which follow.

What is claimed is as follows:

1. A folding cabinet and stand comprising a table top having extension elements hinged thereon and foldable to form an enclosure, a first supporting leg hinged to the table top and on which said table top is arranged to swing, said first leg having a laterally projecting base secured to its lower end to support said cabinet in a vertical position, and a second supporting leg hinged to the table top and arranged to fold under said table top.

2. A folding cabinet and stand comprising a table top having extension elements hinged thereon and foldable to form an enclosure, a first supporting leg hinged to one end of the table top; a pedal base means hinged at the bottom of said first supporting leg to project laterally and to fold up against said supporting leg; a second supporting leg hinged to said table top to fold up under said table top; and the folded portion of the cabinet arranged to fold down against the first supporting leg of said stand, and means connected to one of said legs to form a base to support said cabinet vertically.

3. A folding cabinet and stand comprising a table top having extension elements hinged thereon and foldable to form an enclosure, a first supporting leg hinged to one end of the table top; a pedal base hinged at the bottom of said first supporting leg to project laterally and to fold up

against said supporting leg; a second supporting leg hinged to said table top to fold up under said table top; the folded portion of the cabinet arranged to fold down against the first supporting leg of said stand, means to lock said pedal base and second supporting leg when folded, and automatic means for releasing the pedal base and the second supporting leg when the cabinet is unfolded.

4. A folding supporting means for an ironer comprising a table top for mounting the ironer, cover means for said table top forming a box-like cabinet for the ironer, right and left legs for supporting said table top, means whereby one of said legs may be folded under said table top, the other of said legs having means whereby said box-like cabinet may be swung downwardly adjacent said last named leg, and a base secured to said last named leg to support said cabinet in a vertical position.

5. A folding supporting means for an ironer comprising a table top for mounting the ironer having extension elements hinged thereon and foldable to form an enclosure, a leg at each end of said table top, a pedal base hinged to one of said legs and extending to the other of said legs, one of said legs being hinged to said table top whereby it may be folded under said table top, said table top being hinged to the other of said legs whereby said table top may be swung vertically downward adjacent said last named leg, said last named leg being provided with means forming a base to support said enclosure in folded vertical position.

6. A folding supporting means for an ironer comprising a table top for mounting the ironer, first and second named legs hinged one at each end of said table top respectively, a pedal base hinged to the bottom of said first named leg and extending to said second named leg, a base for the ironer secured to the bottom of said first named leg, said pedal base being foldable upwardly adjacent said first named leg, said second named leg being foldable upwardly under said table top, and said table top while carrying said second named leg being foldable downwardly adjacent said pedal base and first named leg and onto said base for the ironer.

7. A folding supporting means for an ironer comprising a table top for mounting the ironer, first and second named legs hinged one at each end of said table top respectively, a pedal base hinged to the bottom of said first named leg and extending to said second named leg, a base for the ironer secured to the bottom of said first named leg, said pedal base being foldable upwardly adjacent said first named leg, said second named leg being foldable upwardly under said table top, and said table top while carrying said second named leg being foldable downwardly adjacent said pedal base and first named leg and onto said base for the ironer, latch means securing said pedal base and second named leg in folded position, and automatic release means for releasing said latch means by unfolding movement of said table top through more than ninety degrees from said folded position.

8. A cabinet comprising a table top having extension elements hinged thereon and foldable to form an enclosure, legs hinged to the table top for supporting said table top in horizontal position, means whereby said table top and legs may be folded into a vertical rectangular structure, and a base connected to one of said legs for supporting said structure while in a vertical position.

9. A folding support for an instrument or the like comprising a table top for mounting the instrument or the like, legs for supporting said table top in horizontal position, and means whereby said table top and legs may be folded into a vertical position, latch means for holding one of said legs in folded position which automatically latch said last named leg by the folding operation and automatically unlatch said last named leg by unfolding said table top beyond the horizontal while said one leg remains in vertical position.

10. A folding supporting means for an instrument or the like comprising a table top for mounting the instrument or the like, legs for supporting said table top in horizontal position, and means whereby said table top and legs may be folded into a vertical position, latch means for holding one of said legs in folded position, and having means for automatically releasing said latch means during tilting movement of said table top above horizontal position.

11. A folding supporting means for an instrument or the like comprising a table top for mounting the instrument or the like, legs for supporting said table top in horizontal position, a pedal base on one of said legs, and means whereby said table top, legs, and pedal base may be folded into a vertical position, and means on one of said

legs for supporting said supporting means in folded vertical position.

12. A folding supporting means for an instrument or the like comprising a table top for mounting the instrument or the like, legs for supporting said table top in horizontal position, a pedal base on one of said legs, and means whereby said table top, legs, and pedal base may be folded into a vertical position, latch means for holding one of said legs and said pedal base in folded position, said latch means having means automatically effective to latch said legs and pedal base when folded and automatically effective to unlatch said legs and said pedal base by tilting said table top above horizontal position.

13. A folding supporting means for an instrument or the like comprising a table top for mounting the instrument or the like, legs for supporting said table top in horizontal position, a pedal base on one of said legs, and means whereby said table top, legs, and pedal base may be folded into a vertical position, latch means for holding one of said legs and said pedal base in folded position, said latch means having means for automatically releasing said latch means during tilting movement of said table top above horizontal position.

KENDALL CLARK.
